CLAIM

The ornamental design for a single-sole shoe with stripe, sole, and contrasting upper, as shown and described.

DESCRIPTION

FIG. 1 is a perspective view of a single-sole shoe with stripe, sole, and contrasting upper, where the portions of the upper that contrast with the sole and stripe are indicated by cross-hatch shading, showing our new design;

FIG. 2 is a first side view thereof;

FIG. 3 is a second side view thereof;

FIG. 4 is a top view thereof;

FIG. 5 is a bottom view thereof;

FIG. 6 is a front view thereof; and,

FIG. 7 is a back view thereof.

The broken lines illustrating the channel on the sole in the above described Figures are for illustrative purposes only and form no part of the claimed design.
